UNITED STATES PATENT OFFICE.

CLARA T. HARDING, OF BLAIRSVILLE, PENNSYLVANIA.

CAN-OPENER.

1,125,020.

Specification of Letters Patent.

Patented Jan. 12, 1915.

Application filed March 25, 1914. Serial No. 827,126.

To all whom it may concern:

Be it known that I, CLARA T. HARDING, a citizen of the United States, and a resident of Blairsville, in the county of Indiana and 5 State of Pennsylvania, have invented a new and Improved Can-Opener, of which the following is a full, clear, and exact description.

This invention relates to improvements in 10 can openers and has for an object to provide an improved structure wherein the opener may be operated so as to move around the can, or the can may be moved in respect to the opener.

15 Another object of the invention is to provide a guide and holding member for a can which will receive cans of various sizes and an adjustable cutting member co-acting with said guide.

20 In carrying out the objects of the invention, a body is provided which is formed with downwardly extending side members that act as guides for a can, said downwardly extending members or flanges diverging so as to receive cans of various sizes.

25 Co-acting with the body is a traveling cutting member which is supplied with adjusting means, designed to press against one end of the body for causing a proper movement 30 of the cutting member.

In the accompanying drawings—Figure 1. is a sectional view through Fig. 2 on line 1—1; and Fig. 2 is a top plan view of the opener shown in Fig. 1.

35 Referring to the accompanying drawings by numeral, 1 indicates a table or support of any desired kind, to which is connected a standard 2 by a suitable set screw 3, standard 2 being provided with ears 4 and 5, 40 which co-act with the set screw 3 for presenting a clamping structure. The standard 2 is designed to extend upwardly through an opening 6 in an extension 7 of body 8. The extension 7 in body 8 is provided with a slot 9, in which a traveling 45 sliding member 10 is guided. Member 10 is provided with grooves 11 for slightly overlapping the side walls of the slot 9. Member 10 is also provided with a notch 12 for 50 accommodating the cutter 13 held in place by a suitable journal or pin 14.

The upper part of the sliding member 10 is rigidly connected in any desired manner to a screw 15, which screw extends through 55 an upstanding member 16 arranged on body

8. The screw 15 adjacent the upstanding member 16 is provided with a threaded member 17, which acting on the screw and on upstanding member 16, causes the member 10 to travel along slot 9 and to press into 60 a can 18 when the same is in a position shown in Fig. 1. In order to hold can 18 properly in place, body 8 is provided with depending flanges 19, 20, which flanges diverge as clearly shown in Fig. 2. This allows for the reception of cans of various sizes. When a can of any desired size is placed substantially as shown in the drawing, the nut or operating member 17 is actuated until knife 13 presses into the can 70 whereupon the can is rotated manually. Body 8 is held stationary by the standard 2 and upon a complete rotation of the can, the top part will be severed without the liability of spilling any of the contents. 75

Of course it will be evident that the cutter could be used without the standard 2, but in this instance, the can must be held by some means either manually or otherwise and the cutter rotated. 80

What I claim is:—

1. In a can opener of the class described, a body provided with an upstanding member at one end and diverging downwardly extending flanges extending from the opposite side of said body to said upstanding member, said body being also provided with a projection on the opposite end from said upstanding member, said projection being formed with a slot, said body being also 85 formed with a slot merging into the first-mentioned slot, a traveling guide arranged to move in said slots, a cutting member connected with said traveling guide and arranged to operate on the same face of said 90 body as said diverging flanges, a screw member connected with said traveling member, and a nut co-acting with said screw member and with said upstanding member, for causing a movement of said traveling member 100 longitudinally of said slots.

2. In a can opener of the class described, a body substantially triangular in shape, said body having a pair of depending flanges along two of its edges, an upstanding member on the opposite side of said body at the point of juncture of said depending flanges, said body having a slot extending normal to said upstanding member, a traveling member mounted for movement in said slot, a 110

screw connected with said traveling member and extending through said upstanding member, a nut coacting with said upstanding member and engaging said screw for moving the screw and the traveling member longitudinally of said slot, and a cutter arranged on said traveling member, said cutter forcing a can against said depending flanges when said nut is tightened whereby the cut-

ter is adapted to cut the top of the can upon 10 the rotation of said body.

In witness whereof I have signed my name to this specification in the presence of two subscribing witnesses.

CLARA T. HARDING.
